CLAIM

The ornamental design for a frame for a combined cushion and frame module for patient interface, as shown and described.

DESCRIPTION

FIG. 1 is a front perspective view of a frame for a combined cushion and frame module for patient interface showing a first embodiment of our new design;
FIG. 2 is a perspective view of the frame shown in isolation;
FIG. 3 is a front view thereof;
FIG. 4 is a rear view thereof;
FIG. 5 is a top view thereof;
FIG. 6 is a bottom view thereof;
FIG. 7 is a left side view thereof;
FIG. 8 is a right side view thereof;
(Continued)

FIG. 9 is a reverse perspective view thereof;
 FIG. 10 is a front perspective view of a frame for a combined cushion and frame module for patient interface showing a second embodiment of our new design;
 FIG. 11 is a perspective view of the frame shown in isolation;
 FIG. 12 is a front view thereof;
 FIG. 13 is a rear view thereof;
 FIG. 14 is a top view thereof;
 FIG. 15 is a bottom view thereof;
 FIG. 16 is a left side view thereof;
 FIG. 17 is a right side view thereof; and,
 FIG. 18 is a reverse perspective view thereof.
 The broken lines in the drawings depict environmental structure and form no part of the claimed design.

1 Claim, 8 Drawing Sheets
